UNITED STATES PATENT OFFICE

LOUIS BURGER, OF CHICAGO, ILLINOIS.

DESIGN FOR A SPOON.

SPECIFICATION forming part of Design No. 22,242, dated February 28, 1893.

Application filed December 1, 1892. Serial No. 453,785. Term of patent 3½ years.

To all whom it may concern:

Be it known that I, LOUIS BURGER, a citizen of the United States, residing at Chicago, in the county of Cook and State of Illinois, 5 have invented and produced a new and original Design for Spoons, of which the following is a specification.

The leading feature of my design is the head and bust of a woman supported by caryatides, substantially as shown in the drawing, 10 and forming the head or end portion of the handle, and the shank-portion comprises the

representation of a female figure, such as Columbia, shown with arms lifted and surmounted by a sphere, which in turn is surmounted 15 by the caryatides.

What I claim as new, and desire to secure by Letters Patent, is—

The design for a spoon, substantially as shown and described.

LOUIS BURGER.

DOUGLAS DYRENFORTH,
